UNITED STATES PATENT OFFICE.

WALTER T. KRAUSCH, OF LA GRANGE, AND ERNST F. WEBER, OF CHICAGO, ILLINOIS.

TIE-SAWING CAR.

1,243,189.

Specification of Letters Patent.

Patented Oct. 16, 1917.

Application filed May 7, 1917. Serial No. 167,133.

To all whom it may concern:

Be it known that we, WALTER T. KRAUSCH and ERNST F. WEBER, citizens of the United States, and residents of La Grange, in the county of Cook and State of Illinois, and of Chicago, in the county of Cook and State of Illinois, respectively, have invented certain new and useful Improvements in Tie-Sawing Cars, of which the following is a description, reference being had to the accompanying drawings, which form a part of our specification.

Our invention relates to a car that is especially adapted to move or run on rails (laid on the ties to be saved) by means of its own motive power, which power is also adapted to operate the sawing mechanism; the sawing mechanism being adjustably mounted on the car so as to permit it to be swung into and out of operative position.

The invention contemplates a construction whereby both ends of the ties may be simultaneously cut to the desired depth and on opposite sides of the rails, in order that the portions intermediate of the cuts may be subsequently removed with a suitable adz and thus enable the placing of suitable tie-plates beneath the rails. The construction enables the ties to be cut to any desired depth and in a uniform manner, while at the same time permitting the cut portions to be quickly removed so that the operation of tie-cutting or adzing may be accomplished in materially less time than has been the case where this operation is entirely manually performed by the use of an adz.

The construction and its advantages will be more fully understood and comprehended from the following detailed description of the accompanying drawings, wherein:

Figure 1 is a side elevation.

Fig. 2 is an end elevation thereof, with portions shown in section.

Fig. 3 is a detail sectional view, taken on the line 3—3 of Fig. 1, looking in the direction of the arrows.

In the particular exemplification of the invention, it comprises a suitable frame 10, shown preferably composed of channel iron and constituting the side sills, which are secured together by suitable cross-sills shown at 11 in dotted lines in Fig. 1; the under-frame or longitudinal sills being provided with suitable hangers or journal boxes for the journals of the wheels 12, which latter

are adapted to run on the rails 13 of the road-way.

The underframe is provided with a suitable floor indicated at 14 in Fig. 2. The car is also provided with an internal combustion motor, indicated at 15 in Fig. 1, of any suitable construction and capacity; the motor being supported by suitable framework, as indicated at 16. As the motor forms no part of our invention, a specific description thereof will not be entered into.

The longitudinal members 10 of the underframe are provided with suitable pillows or bearing blocks 17 which provide bearing for a transversely disposed shaft 18 to which is secured a sprocket-wheel 19 which receives the sprocket chain 20. The chain 20, in turn, is driven off of the power or driving-shaft 21 of the motor, see Fig. 1. The counter-shaft 18 is also provided with gears 22 and 23 that are secured thereto so as to rotate with the shaft. The gear 23 is adapted to mesh with gear 24 which is adapted to idle on an independent axis and also to mesh with a gear 25 which is feathered or slidably keyed on a shaft 26 by means of the key 27, so that gear 25 may be moved lengthwise of shaft 26 into and out of operative relation with the idler 24.

The shaft 26, which is rotatably mounted in suitable hangers 28 secured to the underside of the longitudinal sills, also has a gear 29 feathered or slidably mounted on shaft 26 so as to be moved into and out of operative relation with the gear 22 of shaft 18. In the particular exemplification of the invention, the two gears 25 and 29 are shown secured to a sleeve 30 which is slidably keyed or feathered on the shaft 26 so that both gears 25 and 29 may be controlled by a single shifting element. For this purpose the sleeve 30 is provided with a circumferential groove 31 adapted to receive the inwardly presented trunnions or ends of the lower bifurcated end of a shifting lever 32, which is pivoted at 33 in a suitable manner on the floor or underframe of the car, see Fig. 3. As is apparent from the construction shown, with the gear 29 in mesh with gear 22, power is transmitted to the counter-shaft 26 in a given direction, while a slight shifting of lever 32 will move gear 29 into neutral or inoperative position before gear 25 has been moved into operative relation with the idler 24. Further oscillation or

movement of lever 32 to the left in Fig. 3 will shift the coupled gears 25-29 so as to cause gear 25 to mesh with idler 24 and thus transmit power to counter-shaft 26 in the reverse direction.

The shaft 26 is provided with a pair of sprocket wheels 34 and 35 which are preferably loosely mounted on the shaft, but held against movement lengthwise of the shaft. The hubs of both sprockets are provided with suitable clutch-engaging surfaces, as shown in Fig. 3, adapted to effect clutching engagement with a clutch later described. The sprocket-wheel 34 receives a sprocket chain 36 which takes about the large sprocket-wheel 37, shown in dotted lines in Fig. 1, and which is either secured to the journal 38 or to the hub of the wheel 12; while the sprocket wheel 35 receives a sprocket chain 40 which takes about sprocket wheel 41, which, like sprocket wheel 37, may either be secured to the journal 38 or to an extended portion of the hub of the wheel.

Slidably keyed on shaft 26, intermediate of the sprockets 34 and 35, is a clutch 42 which is adapted to have clutching engagement with both sprockets 34 and 35 so as to transmit power from shaft 26 to either one of the sprockets when the clutch has been shifted in the proper direction. The clutch 42 is operated by a lever 43 fulcrumed at 44 in a suitable manner to the floor or under-frame so as to shift or oscillate in a direction transversely of the car and therefore longitudinally of shaft 26.

With the lever 43 in the position shown in Fig. 3, the clutch 42 is in neutral or inoperative position, so that power will not be transmitted from driven shaft 26 to the car journal or axle 38; while a shifting or oscillation of lever 43 to the right in Fig. 3 will move the clutch 42, which is feathered on shaft 26, into operative relation with sprocket wheel 34 and thereby cause the car to travel at a given speed forward. On the other hand, if lever 43 is shifted to the left in Fig. 3, clutch 42 will then be moved into operative relation with sprocket wheel 35 (which, in the exemplification, is shown of larger diameter than 34) and cause the car to be moved forwardly at a greater speed.

The forward end of the car-frame, at a point forward of the front journal, is preferably made with the upwardly bent or inclining portion 10^a, terminating in a horizontally presented portion, so as to provide a support or bearing for the pivotal point of the cutting mechanism at a suitable point above the floor-level of the car in order to permit proper movement of the cutting mechanism which will now be described.

The two side frame-members are each provided with suitable bearings or blocks 45, 45 in which a shaft 46 is journaled; the shaft 46 extending transversely of the car

or machine, as shown in Fig. 2. The shaft 46 is provided with a pulley 47 secured thereto so as to rotate therewith; the pulley 47 being adapted to receive a belt 48 which takes about a pulley 49 secured on the power 70 or driving shaft 21 of the motor. The shaft 46 is also provided with a sprocket wheel 50, loosely mounted on the shaft 46 and arranged to be controlled by a suitable clutch 51 feathered on shaft 46 and adapted to be operated by a lever 52. Movement of lever 52 either to the right or to the left will remove the clutch into and out of operative relation with the sprocket wheel 50.

The shaft 46 is also provided with a vertically disposed and swinging frame 53, preferably composed of the two side members, as shown in Fig. 1, which are suitably braced and secured together by the transverse members 54 so as to provide the rectangular frame shown in Fig. 2, which is adapted to swing vertically about the shaft 46.

The upper end of the frame is provided with suitable bearings at 55 in which is 90 rotatably mounted a shaft 56. Secured to shaft 56 so as to rotate therewith is a sprocket-wheel 57 which is adapted to receive a sprocket-chain 58 which takes about and meshes with sprocket wheel 50, so that 95 power will be transmitted from shaft 46 to shaft 56 when clutch 51 has been moved into clutching engagement with sprocket 50.

Mounted on shaft 56, so as to rotate therewith, is a pulley-wheel 59, receiving a belt 100 60 which passes about a pulley 61 secured to a shaft 62 rotatably mounted in suitable hangers 63 at the lower ends of the vertically disposed frame members 53. As more clearly shown in Fig. 2, the bearings or hangers 63 are preferably removably secured at the lower ends of the frame members 53 by means of the bolts 64.

The frame-members 53 are of such length as enables them to depend below the car-floor 110 to a point into proximity with the rails on which the car operates. The angle of inclination from the perpendicular of the frame 53 is controlled by means of a rod 65 which is preferably pivoted at 66 to a portion of the car under frame, see Fig. 1, so as to permit the rod to swing in a vertical direction and extend somewhat forward of the vertical plane of the pivotal point of frame 53, namely into a vertical plane forward of the shaft 46. One of the cross members 54 of the vertically swinging frame is provided with a split clamp member 67, see Fig. 2, pivoted at 68 and adapted to permit the rod 65 to extend therethrough; 120 the split ends of the clamp-member 67 being provided with a screw bolt receiving the handle or butterfly nut 69 whereby the split ends of the clamp-member 67 may be drawn together into firm clamping engage- 130

ment with the rod 65 after the frame has been swung into the desired inclination.

Both ends of shaft 62, which extend beyond the bearings 63, are each provided with sleeves 70 keyed to the shaft so as to rotate therewith; and the opposite ends of both sleeves are arranged to receive the circular saws 71, 71, which are firmly clamped in place by suitable nuts and washers, indicated at 72, so as to compel the saws to rotate with the sleeves and therefore with the shaft 62.

The shaft 62 has adjustable relation with the frame members 53, because the latter are provided with slots, as shown at 73 in Fig. 2, through which the bolts 64 pass.

The saws are preferably provided with the segmental guards 74, disposed over the top of the saws; the guards being preferably of sheet metal and supported by the arms 75 secured to opposite sides of the guards and somewhat radially disposed, as shown in Fig. 1, with the inner ends of the arms 75 bearing against the sides of the lower ends of the frame-member 53.

In order that the belt 60, whereby power is transmitted from shaft 56 to shaft 62, may be maintained under proper tension, we provide the set-screws 76 which engage with the upper ends of the arms of bearing members or hangers 63. As the hangers 63 have adjustable relation with the frame 53, by means of slots and bolts 73, 64, the set-screws 76 may be turned so as to force the hangers downwardly and therefore also cause shaft 62 to move downwardly, which will place the belt 60 under tension; the set-screws 76 preventing the hangers 63 and shaft 62 from being moved upwardly through the action of the belt.

As is evident from the construction shown and described, the cutting mechanism can be swung vertically out of operative position, while the car is transported from place to place until the point is reached where the ties are to be cut or sawed, when the lower end of the frame of the sawing mechanism is swung downwardly, which is accomplished by releasing the clamping nut 69 of the clamping member 67 so that the latter may slide along rod 65. After the frame has been swung downwardly to the point where the saws 71 will produce a cut in the tie indicated at 77 in Fig. 2, to the desired depth, the clamp-nut 69 is screwed up so as to cause the clamping member 67 to have firm gripping relation with rod 65 and thereby lock the swinging frame in its adjusted position.

The motor being in operation, power is transmitted to shaft 46 through the medium of belt 48 and pulley 47; the lever 52 is then oscillated so as to throw clutch mechanism 51 into clutching engagement with the sprocket-wheel 50, thereby causing power to

be transmitted to shaft 56 in the upper part of the swinging frame and this, in turn, will transmit power to the saw-holding shaft 62 by means of pulley 59, belt 60 and pulley 61. The swinging frame having been adjusted to provide a cut of desired depth in the ties, the car may travel along the rails at a suitable speed, controlled through the operation of clutch-operating lever 43; while the direction of travel is determined by the gear-shifting lever 32.

It is apparent that one or two operators can perform the operation of tie-cutting, one operator preferably controls the movements of the car, relative to the road-bed or track, while the other is preferably in charge of the operation of the sawing or cutting mechanism; or a single operator might be employed. The device enables a considerable number of ties to be quickly cut or sawed to the desired depth and with a uniform cut, while the sawed portions of the tie may be readily removed with a suitable adz in the hands of an operator or operators, who follow up the sawing car. Our improved car enables these operations to be accomplished in a very much less time and with greater accuracy than has been the case where the portions of the ties have been entirely removed manually by the use of an adz; while at the same time our construction provides cut-out portions of uniform depth throughout, so that the tie-plate may not only be disposed, throughout its length, in substantially the same horizontal plane, but will also be flush with the tie and have bearing on the tie throughout its entire lower surface.

By providing a vertically swinging frame, as shown in the drawings, wherein a portion of the frame extends to a considerable distance above the pivotal point or shaft 46, with the upper end provided with a large pulley, power is not only transmitted to the saws so as to have the latter rotate at a sufficient speed, but a counter-balanced swinging frame is provided which enables easy manipulation or adjustment of the frame into the desired positions.

We have illustrated in the drawings and described in the foregoing specification what we believe to be the simplest and best adaptation of the invention, but it may have expression in somewhat different mechanical form without, however, departing from the spirit of our invention.

What we claim is:

1. A tie-sawing car provided with a motor whereby the car may be propelled, the side sills of the car underframe being inclined upwardly beyond the end of the car, a power-shaft extending transversely of the car and rotatably mounted on said inclined portions of the side sills, controllable means for transmitting power from the motor to

4

said shaft; a frame disposed transversely of the car and journaled intermediate of its ends on said power-shaft so as to swing vertically and thereby bring its lower end into proximity with the ties, a counter-shaft rotatably mounted in the upper end of said frame and in operative relation with said power-shaft, a second counter-shaft rotatably mounted in the lower end of said frame and adapted to extend across the rails, means intermediate of the last mentioned shafts whereby power is transmitted from the one at the upper end of the frame to the shaft at the lower end of the frame, a plurality of saws arranged in pairs at the ends of said last mentioned shaft so as to be disposed on both sides of the rails, and adjustable means intermediate of said vertically swinging frame and the car whereby said frame will be held in its adjusted position relative to the ties.

2. A tie-sawing car provided with a motor whereby the car may be propelled, a power-shaft rotatably mounted and extending transversely of the end of the car, means for transmitting power from the motor to said shaft, a frame disposed transversely of the car and journaled intermediate of its

ends on said power-shaft, said frame being adapted to swing vertically and depend beneath the car into proximity with the ties, adjustable means intermediate of said frame and the car whereby the frame will be held in its adjusted position relative to the ties, a counter-shaft rotatably mounted transversely in the upper end of said frame, controllable means intermediate of the power-shaft and said counter-shaft, whereby power is transmitted from the former to the latter, hangers adjustably secured to the lower end of said frame, means whereby the adjustment of said hangers lengthwise of the frame is obtained, a second counter-shaft rotatably mounted in said hangers and arranged to extend across the rails, means intermediate of the two counter-shafts whereby power is transmitted from the first mentioned counter-shaft to the second mentioned counter-shaft, and a plurality of saws arranged in pairs at the ends of the second counter-shaft and on opposite sides of the rails.

WALTER T. KRAUSCH.
ERNST F. WEBER.
